RAILWAY TERMINAL COMMUNICATING
SYSTEM

Caleb Drake and Andrew Langdon, Rochester,
N. Y., assignors to General Railway Signal
Company, Rochester, N. Y.

Application May 26, 1932, Serial No. 613,676

28 Claims. (Cl. 246—2)

This invention relates to a communicating system in connection with train starting in large railway terminals, and more particularly relates to a system providing alternative communication between the conductor, gateman, and train director in such a railway terminal.

In large railroad terminals a considerable number of platforms is necessary for loading passengers or baggage on a train occupying the adjacent track. Inasmuch as these platforms may be so located that they are not all visible from the train director's location, it is inconvenient for either the train director to know when such trains are prepared to leave, or for the train conductor and gateman to be informed concerning the time which the train dispatcher wishes to start the train.

This information is of great value to the parties concerned, as the sequence of traffic movements through the terminal can be more efficiently planned if accurate information is available concerning the readiness of trains to start. The conductors and gatemen in such terminals are hindered by the lack of communication means as the gatemen must be informed when each particular train is in position and ready to load passengers, and it is convenient and efficient to inform the conductor and train director when the gateman has allowed all the passengers to board a particular train.

In view of the above, it is proposed in accordance with this invention to provide a system whereby alternate communication between the train conductor, train director and gateman can be obtained by means of small signals arranged to be controlled at stations conveniently located for each of the above mentioned parties.

Other objects, purposes and characteristic features of the invention will appear as the description thereof progresses, during which references will be made to the accompanying drawings which show the invention in a manner to make it easily understood, rather than with the view of showing the particular construction preferably employed in practice, and in which:—

Fig. 1 shows a typical layout of a communicating system according to this invention with the various apparatus indicated diagrammatically;

Fig. 2 is an operating circuit involved in a single platform apparatus and its accompanying tower apparatus according to this invention; and

Fig. 3 is a modification of the circuit shown in Fig. 2 possessing the same characteristics and operating sequence.

55 A railroad terminal, which is large enough to

warrant the installation of a communicating system as disclosed in this invention, has a considerable number of platforms located between the tracks, and such platforms usually extend for a distance long enough to permit the loading of two 5 trains placed end to end on any one track. The length of such loading platforms usually makes it necessary to employ several communicating stations for the train conductors, or such a number that one is conveniently located wherever the 10 train may be stopped along the platform. In the typical layout shown in Fig. 1, four conductor stations are indicated by the dotted rectangles C, C¹, C² and C³ included in the large dotted rectangle enclosing platform 1 apparatus. 15

The length of the loading platforms also makes it desirable to employ two or more passages to a concourse leading from the platform to the station. It is usually the custom to station a gateman at each of such passages, and it is proposed to locate two gatemen stations at each passage, one concerning each track associated with the particular platform. Thus, for each track, two gateman stations are employed, one at each passage, which are shown in Fig. 1 by the 25 dotted rectangles GS and GS¹ also included in the large dotted rectangle enclosing platform 1 apparatus.

An east relay panel and a west relay panel are also included in each track apparatus from 30 which connections are made to all the conductor stations C, C¹, C² and C³ in parallel and to the gateman stations GS and GS¹ in parallel. This track 1 apparatus is duplicated for track 2 which is indicated by a second dotted rectangle, and the 35 two may be said to constitute a single platform apparatus as the platforms are usually located between two tracks and arranged to load trains on either side. It is now evident that the apparatus included in the large rectangle enclosing platform 1 apparatus is duplicated for each platform in the terminal, unless a platform may be adapted to load a train on one side only in which case the apparatus for a single track will constitute this platform apparatus. 45

In the particular terminal layout in Fig. 1, two towers are shown, each of which contains apparatus governing the traffic through its particular side of the terminal. A train director is stationed at each of these towers, who operates 50 traffic controlling apparatus to line routes and release trains through his particular territory. A train director's communicating panel for each track is placed at each tower and connected to each associated track apparatus as is more fully 55

described hereinafter. Where one tower only is used, the apparatus shown in west and east towers would be located in the single tower.

The conductor's communicating station C, referring to Figs. 2 and 3, consists of two banks of color light signals, G, Y and R and two push buttons 5 and 5^a, each so located as to be associated with its particular signal bank. Each of these signal banks governs the starting of trains in its particular direction which direction may be suitably marked thereon, such as W and E as shown, or the station may be so positioned that the governing direction of each bank is readily apparent.

15 The gateman's communicating station GS consists of two direction indication lights W and E with push buttons 74 and 74^a, each associated with a particular direction indicating light. The direction indicated by these lights may similarly 20 be designated by the letters W and E or by the positioning of the station as previously described.

The train director's communicating apparatus comprises a single bank of color light signals, G, Y and R, an acknowledging contactor A and a 25 cancelling contactor CB. These contactors and signals are also suitably marked to designate the track to which they communicate, such as track No. 1, as shown in Figs. 2 and 3, by reference character W¹, and are located together with their 30 accompanying relays in the west tower. It is also to be understood that this tower apparatus is duplicated in the east tower and arranged to communicate with conductors of trains on its particular track which trains are to make eastward 35 moves.

To simplify in disclosing the operation of the present system, it is considered sufficient to trace in detail only one of the many duplicate channels of communication, or specifically in Figs. 2 and 40 3, the communication channel between the conductor of a west bound train at station C, the gateman at station GS and the train director at his W¹ panel. By referring to Fig. 1, it can be seen that the above communicating channel only 45 involves the west signals and associated push button controls of stations C and GS and only the west relay panel of track 1 apparatus.

This apparatus which is concerned is shown in Figs. 2 and 3 with the wiring connections shown 50 in detail, and a section of the associated track is indicated diagrammatically to facilitate in showing the relation of the occupancy thereof to the operation of the system. Other apparatuses essential to the system are included in Figs. 2 and 55 3, such as the transformers TF¹ and TF², used to supply the proper voltage of alternating current for lighting the color light signals.

The arrangement shown in Fig. 1 includes five 60 common wires extending between the two towers and leading to each track apparatus in the system, which is the apparatus inclosed in the dotted rectangle R of Figs. 2 and 3. Two of these wires BX and CX are connected to a suitable external source of alternating current electrical energy 65 and carry energy to all the transformers in the system such as TF¹ and TF² in Figs. 2 and 3. Suitable direct current power apparatus P is conveniently located in the system which is to supply 70 remaining three of the aforesaid common wires. This power supply may be two storage batteries B¹ and B², as shown, connected in series and suitably charged from the alternating current wires BX and CX through a transformer and rectifier arrangement as indicated. These two 75

batteries in series supply positive potential to the BL wires, negative to the NL and the center potential or common wire is connected to the CL wire. These batteries may be omitted and the rectifiers only employed to supply direct current power, in which case the rectifiers must be of sufficient capacity to carry the maximum load.

Having described such apparatus of the present invention which is not of well established design, it is believed, that the usefulness and the 10 various interrelated function of the system and circuits of this specific embodiment of the present invention will be more readily understood by further description being given from the standpoint of operation.

Operation

Considering now, by referring to the embodiment shown in Fig. 2, that a west bound train is occupying a section of the track T2 and that the conductor is ready to load passengers, the 20 following communication is accomplished. The conductor presses the west push button 5 at station C which positively energizes relay CS at the local platform and relay TS at the west tower 25 over the following circuit:—beginning at the positive direct current energy wire BL, wires 1, 2 and 3, push button 5 closed, wire 6, contact 7 of relay CP in its de-energized position as shown, wire 8, through a resistor 9 of nominal value, say 50 ohms, wire 10, through the windings of the 30 polarized relay CS, wire 11 to the common potential wire CL. Energy flowing to the relay CS through the resistance 9 as previously traced, also flows over an individual line wire L to relay TS located in the tower, through its windings, 35 wire 12, cancelling contact CB closed, wires 13, 14 and 15, contact 16 of track relay TR¹ energized, wires 17 and 18, contact 19 of track relay TR² in its de-energized position (inasmuch as the train is now occupying the track section T2,) 40 wire 21 back to the common wire CL. In the above circuit, a front contact 188 of relay RP is in multiple with contact 16 of relay TR¹ thus permitting the system to function during switching movements in the track section T1 providing 45 the signal S1 is at stop.

The completion of the above circuit causes the polarized relays CS and TS to swing their contacts to the right, which lights the conductor's red light R at station C from the secondary of 50 transformer TF² over wire 23, contact 24 of relay CS swung to the right, wire 25, contact 26 of relay CP in its de-energized position, wire 27, through the lamp of the conductor's red signal R, wires 28 and 29 back to the secondary of transformer TF².

When the contact 33 of relay TS swings to the right the two relays TS and CS are held in such position through a stick circuit, through a resistor 34 which is substantially larger than the resistor 9, say of about 100 ohms, over a circuit from the positive bus BL, wires 30, 31 and 32, contact 33 swung to its right position, resistor 34 to the line wire L, and thence in multiple through 60 the two relays to thereby positively energize the relays TS and CS through their circuits to common or CL, as previously traced.

The moving of contact 38 of relay TS to the right energizes relay TNP from the positive wire 70 BL over wires 30, 31 and 35, through the windings of relay TNP, wires 36 and 37, contact 38 of relay TS, wires 39, 40 and 41 back to the negative potential wire NL. This picks up contact 43 of relay TNP which lights the train director's 75

red light R from the secondary of transformer TF1 over wire 42, contact 43 of relay TNP in its energized position, wire 44, contact 45 of relay TRP in its de-energized position, wire 46, 5 through the lamp of the train director's red signal R, wire 47 back to the secondary of transformer TF1.

It will now be seen that the conductor, by pressing a push button has indicated to the train director through lighting a red signal light that he is prepared to load passengers, but he also has a red signal indication which indicates that the train director has not yet given permission to load that particular train. When the train director 10 desires to convey such information to the conductor he presses his acknowledging contactor A which applies energy of a reverse polarity to the polarized relays CS and TS over the following circuit:—beginning at the negative potential wire NL, wires 41 and 48, contact 49 of relay TNP in 15 its energized position, wire 50, contact 82 of relay TRP in its de-energized position, wire 53, contact 54 of acknowledging contactor A in its depressed position, wire 55 through a resistor 56 20 of approximately the same value as resistor 9, to the line wire L thereby going to common through the windings of relays CS and TS over their common circuits previously traced.

It will be noticed that the application of current of reverse polarity to the polarized relays CS and TS just described is superimposed on the existing energization of their coils, which decreases the current in the coils to such an extent that the relays will release their armatures, there- 25 by interrupting their holding circuit at contact 33 of relay TS. Contact 38, leaving its right extreme position, interrupts the circuit from the relay TNP to the NL energy wire but a substitute circuit is established during the depression of the 30 acknowledging contactor A by wire 55, its own contact 86, wire 87, acknowledging contact 88 depressed, wires 89, 90, 40 and 41 to the energy wire NL. This maintains relay TNP in its energized position which sustains the application of 35 reverse polarity to relays CS and TS thereby causing their contacts to swing to the left where a holding circuit is established from the NL energy wire over wires 41, 40, 90 and 57, contact 33 of relay TS to the left and resistor 34 to the 40 line wire L, which maintains this energization of relays CS and TS after the acknowledging contactor A has been released.

To obviate the possibility of the voltages of the two batteries B¹ and B² differing sufficiently 45 to prevent an effective bucking of the holding current in the relays CS and TS during the operation just described, a resistor 34 is placed in the holding circuit which resistor is of a substantially greater value than the resistors 9 and 50 55 which are employed in the operating circuits. This introduces a sufficiently greater voltage drop in the holding circuit than in the operating circuit to make the actual operating voltage at the relay coils always exceed the holding voltage 60 thereby insuring proper operation.

Relay TNP is de-energized by interrupting its 65 circuit at contact 33 which is opened by releasing the acknowledging contactor A, and when the contacts of relay TS swings to the left energy is applied to the relay TRP from the energy wire BL over wires 30 and 60, windings of relay TRP, wires 59 and 58, contact 38 of relay TS swung to the left, wires 39, 40 and 41 to the energy wire NL.

The train director's red signal light is now extinguished by interrupting its circuit at contact 49 of relay TNP in its de-energized position, and the yellow signal light is energized from transformer TF1 over wire 42, contact 43 of relay TNP in its de-energized position, wire 61, contact 62 5 of relay TRP in its energized position, wire 63, through the yellow signal lamp, wire 47 back to transformer TF1.

Relay CS swinging its contacts to the left extinguishes the conductor's red signal light by 10 interrupting its circuit at contact 24 and applies energy to the conductor's yellow signal light and the gateman's directional light W from transformer TF2, wire 23, contact 24 swung to the left, wire 69 and then through two parallel paths, 15 one being over wire 70, conductor's yellow signal lamp Y, wire 28, and the other being over wire 71, gateman's directional light W, wire 72, and both paths returning to the transformer TF2 by wire 29. The relay CP is also energized when 20 the contacts of relay CS are swung to the left by energy from wire BL, wires 1 and 64, windings of relay CP, wires 65 and 66, contact 67 of relay CS swung to the left, wire 68 to energy wire NL.

It will be seen that the conductor and gateman now have permission to load the train, whereby the gateman, having information concerning the direction of the train, opens the proper gate and allows passengers to pass to the 30 train. When the last of the passengers has been admitted, the gateman allows sufficient time for the last one to reach the train and then presses his proper directional push button, which in this case is push button 74. This again applies current of normal polarity to the relays CS and TS from the energy wire BL over wires 1, 2 and 73, push button 74, wire 75, contact 7 of relay CP in its energized position, wire 8 and resistor 9 to the line wire L. This current of normal 40 polarity is superimposed on the existing current of reversed polarity of the relays CS and TS which swings their polarized contacts again to the right by first breaking their holding circuit through contact 33 of relay TS to the left and the 45 resistor 34 in a similar manner to the reverse operation due to the train director's acknowledging act just described.

The relay CP is constructed so that its action in returning to its de-energized position is sufficiently retarded to allow the contacts of relay CS to swing from one extreme position to the other before its contacts have left their energized position. Consequently, the relay CP having been previously energized, remains in its 50 energized position during the shifting of the polarized contacts of relay CS, and after these contacts have assumed their right hand position the relay CP is maintained energized from the energy wire BL, wires 1 and 64, winding of relay 60 CP, wires 65 and 76, its own contact 71 in its energized position, wire 78, contact 67 of relay CS swung to the right, wire 68 to energy wire NL.

The conductor's yellow signal and the gateman's directional signal are now extinguished by 65 breaking their energizing circuit at contact 24 of relay CS swung to the right and the conductor's green signal is energized from transformer TF2 over wire 23, contact 24 of relay CS swung to the right, wire 25, contact 26 of relay CP energized, 70 wire 79, through the conductor's green signal lamp, wires 28 and 29 back to transformer TF2.

The relay TRP, like relay CP, is made so that its contacts are slow in breaking from their energized positions which enables its contact 82 to 75

remain in its energized position while the polarized contact 38 of relay TS swings from its left to its right hand position and thereby energizes relay TNP as previously described. The relay 5 TNP, being energized, closes a circuit to retain relay TRP in its energized position from the energy wire BL, wires 30 and 60, winding of relay TRP, wires 59 and 81, its own contact 82 in its energized position, wire 59, contact 49 of relay 10 TNP in its energized position, wires 48 and 41 to the energy wire NL.

The relay TNP, assuming its energized position, extinguishes the train director's yellow signal light by interrupting its energizing circuit at its 15 contact 43. The relay TRP, now being in its energized position, lights the train director's green signal light G from the transformer TF¹ over wire 42, contact 43 of relay TNP energized, wire 44, contact 45 of relay TRP energized, wire 20 83, contact 84 of the train director's acknowledging contact A in its normal position, wire 185 through the train director's green signal lamp wire 47 to transformer TF¹.

The conductor, now having a proceed indication, signals the engineer to start the train, and the signal S1 having previously been cleared from the tower and the relay RP de-energized, the train moves out of the track section T2. The train entering track section T1 de-energizes the 30 track relay TR¹ which interrupts the common potential circuit of the relay TS at contact 16 of track relay TR¹ de-energized. This de-energizes the relay TS which interrupts its own holding circuit and the holding circuit for relay CS 35 at contact 33.

The returning of relay TS to a neutral position de-energizes relay TNP at contact 38, and relay TNP in turn de-energizes relay TRP at contact 49. This puts the tower end of the system at 40 rest thereby extinguishing the train director's green signal light by interrupting its circuit at contact 43. In a similar manner, the de-energizing of relay CS de-energizes the relay CP at contact 67 which puts the platform end of the 45 system at rest thereby extinguishing the conductor's green signal light at contact 26.

It may also be convenient for yard switching movements in the terminal to employ a partial operation of the above which is accomplished as 50 follows:—the yardman, ready to make a move from the platform, presses the push button 5 at the conductor's communicating station which lights the red signal light at that station and the corresponding train director's red signal light 55 through the same operation as was previously described. The train director is now informed of the yardman's desire to leave the platform and proceeds to clear the proper signals and acknowledges by pressing his cancelling button CB which 60 interrupts the common circuit thereby extinguishing both red lights and restoring the system to normal again as previously described.

It will now be seen that a sequential communicating system has been provided which allows the 65 conductor to initiate the system by signalling the train director, who then acknowledges by signalling the conductor and gateman, and finally the gateman, at the proper time, signals both the conductor and train director. This is all the 70 communication that is necessary in starting a single train, and when this is completed the train leaves the platform thereby extinguishing the existing signal lights and putting the system at rest.

75 In the above circuit arrangement it is necessary

for a train to be occupying either track section T2 or T3 before the system can be operated as the common circuit for relay CS is only complete when either track relay TR² or the relay TP³, which repeats the track relay TR³, is de-energized. This prevents a mischievous operation by an unauthorized person when a train is not standing at the platform.

It will be noted that the operation of the system is further dependent on the existence of one of several conditions, which are namely:—that the track section T1 be unoccupied or that the signal S1 be at stop or if it is desirable to operate the systems when neither of these conditions exists, a by-pass circuit is provided by wires 15 22, 92 and 93, contact 94 of relay TNP de-energized and wires 95 and 96, or a second by-pass is provided including wires 22, 92 and 97, contact 98 of relay TRP de-energized and wires 99 and 96. A third by-pass circuit is also provided through 20 the acknowledging contactor A depressed over wires 22 and 51; contact 52 of the acknowledging contactor A depressed and wire 91 which prevents the interruption of the common circuit including a contact of either relay TNP or TRP just described, in the event that the train director while acknowledging a communication holds the contactor A depressed for a sufficient length of time to energize relay TRP while maintaining relay TNP energized through contact 88 depressed. 30 The purpose of the by-passing circuits outlined in this paragraph is to permit switching movements involving the clearing of signal S1 while the train is loading passengers. In other words, the automatic cancellation feature provided by 35 the combination of the track section T1 occupied and signal S1 clear is effective only when the last or green indication of the system has been displayed.

It will also be noted that the energizing of both 40 relays TNP and TRP by holding the acknowledging contactor depressed, as was just described, produces a condition which exists when the train director's green light is energized. To prevent a false green indication in this condition, the energizing circuit for the above mentioned green signal is taken through contact 84 which interrupts the circuit when the acknowledging contactor is depressed.

In the above system, the order of communication must be followed in the sequence previously outlined as the gateman is prevented from initiating the system because his control is broken at contact 7 of relay CP which is de-energized and likewise the train director is prevented from 55 initiating the system as his control is interrupted at contact 49 of relay TNP which is de-energized. Also after the system has been initiated, the gateman cannot communicate until after the train director has acknowledged and by so doing 60 swings the polarized relay CS to the left thereby energizing the relay CP and establishing the gateman's control circuit.

It will be noticed that the modified circuit, shown in Fig. 3 differs chiefly from the one just 65 described in that only neutral relays are employed which necessitates the use of two individual line wires connecting each track apparatus with the corresponding tower apparatus as compared to the single wire shown in Fig. 1. However, by the elimination of the polarized circuits, the number of power wires commonly connecting all track apparatus and both towers is decreased to four as compared to the five necessary in the circuit shown in Fig. 2.

Inasmuch as this circuit modification shown in Fig. 3 is equally applicable to the communicating system as the one shown in Fig. 2 and overcomes any objection to polarized circuits which a particular application may produce, it is considered expedient to also discuss its operation in detail.

Assuming the same conditions as previously existed, the conductor initiates the system by pressing the push button 5 which energizes relays C1 and C2 over the following circuits:—beginning at the positive energy wire BL, the relay C2 is energized by current flowing in wire 100, resistor 101, wires 102 and 103, contact 5 depressed, wires 104 and 105 through the windings of relay C2, wires 106, 107 and 108 to the negative energy wire CL. Current in the above circuit to the relay C2 also energizes relay C1 over wire 109, contact 110 of relay D2 de-energized, an individual line wire L¹, contact 111 of relay D1 de-energized, wires 112 and 113, through the windings of relay C1, wires 114, 115 and 116 to the common energy wire CL.

The same conditions, such as the occupancy of track sections and the condition of signals, must exist before this circuit is operable as was essential to the operation of the previous circuit. In the first circuit, however, one of the outlined conditions must exist to complete the common potential circuit, while in this modified circuit, such conditions must exist to complete the holding or stick circuits for the control relays.

Assuming the track section T2 occupied, energy is applied to the relay C1 from the positive wire BL, wire 117, resistor 118, wire 119, cancelling button CB, wires 120 and 121, contact 122 of relay TR² de-energized, wires 123 and 124, contact 125 of relay TR¹ energized, wires 126 and 127, resistor 128, contact 129 of relay C1 energized, wires 130 and 131 to relay C1 and also to relay C2 over line wire L¹ as previously traced. The same provision is made in this system as in the system of Fig. 2, or that is, a front contact 133 is provided on relay RP in multiple with contact 125 of relay TR¹ to permit operation of the system when the track section T1 is occupied and the signal S1 is at stop. This energy returns from the relays to the CL energy wire over the same circuit as before and thereby holds the relays C1 and C2 energized after the return of push button 5 has interrupted the energizing circuit.

The energizing of relay C2, energizes the conductor's red signal light from the transformer TF² over wire 134, contact 132 of relay D2 de-energized, wire 133, contact 134 of relay C2 energized, wire 135, the red signal lamp R, wires 136 and 137 back to the transformer TF². Likewise, the energizing of relay C1, energizes the train director's red signal light from the transformer TF¹ over wire 138, contact 139 of relay D1 de-energized, wire 140, contact 141 of relay C1 energized, wire 142, the red signal lamp R, wire 143 back to the transformer TF¹.

The train director now acknowledges by pressing his acknowledging button A which energizes relays D1 and D2 from the positive bus BL, wire 117, resistor 118, wire 119, acknowledging contactor A, wire 144, contact 145 of relay C1 energized, wire 146 to the individual line wire L² which connects the relays D1 and D2 in parallel. The return circuit for relay D1 to the negative potential wires is by wires 147, 145 and 146 and the return for relay D2 is by wires 148, 107 and 108. The relays D1 and D2 are now held in their energized position by a stick circuit which is the

same as traced for relay C1 as far as wire 127 which is connected to the line wire L² by wire 149, resistor 150, contact 151 of relay D1 energized and wire 152.

The energizing of relay D1 now extinguishes the train director's red signal light at its contact 139 and energizes the yellow signal light from transformer TF¹ over wire 138, contact 139 of relay D1 energized, wire 153, contact 154 of relay G1 de-energized, wire 155, train director's yellow signal lamp Y, wire 143 to transformer TF¹. In like manner, the energizing of relay D2 extinguishes the conductor's red signal light at its contact 132 and energizes the yellow signal light from transformer TF² over wire 131, contact 132 of relay D2 energized, wire 156, contact 157 of relay G2 de-energized, wires 158 and 159, the conductor yellow signal lamp Y, wires 136 and 137 back to transformer TF². The gateman's directional light W is also energized from the transformer TF² over wire 131, contact 132 of relay D2 energized, wire 156, contact 157 of relay G2 de-energized, wires 158 and 160, the gateman's west signal lamp W, wires 161 and 137 back to the transformer TF².

The gateman, now at the proper time previously described, presses his push button 74 which energizes the relay G2 from the positive energy wire BL over wire 100, resistor 101, wire 102, contact 74 depressed, wires 162 and 163, the windings of relay G2, wires 164 and 165 to the negative energy wire CL. Relay G1 is also energized by pressing button 74 as it is connected in parallel with relay G2 by wire 165, contact 110 of relay D2 energized, line wire L¹, contact 111 of relay D1 energized, wires 166 and 167 and back to the negative potential wire CL by wires 168 and 169. Relay G1 being energized completes a holding circuit to maintain relays G1 and G2 energized from the positive energy wire BL, wire 117, resistor 118, wire 119, cancelling contact CB, wires 120 and 121, contact 122 of track relay TR² de-energized, wires 123 and 124, contact 125 of relay G1 energized, wire 173, contact 174 of relay D1 energized and by wire 175 to the parallel circuit connecting relay G1 and G2 just traced.

The energizing of relay G2 extinguishes the conductor's yellow signal light and the gateman's directional light and energizes the conductor's green signal light by the shifting of contact 157 which interrupts the current to wire 158 and completes a circuit through wire 169 to the green signal lamp. Likewise, the energizing of relay G1 extinguishes the train director's yellow light and energizes his green light by the shifting of contact 154 which interrupts the current to wire 155 and completes a circuit through wire 173 to the green signal lamp.

The train now moves out of the track section T2 thereby interrupting the stick or holding circuit for relays C1, D1 and D2 by de-energizing relay TR¹, relay RP also being down due to clearing of signal S1. The de-energizing of relay D1 interrupts the previously traced holding circuit for relays G1 and G2 at contact 174, which puts the system at rest thereby extinguishing the train director's and the conductor's green signal lights.

This modified circuit possesses the same operating sequence as the circuit previously described and requires the existence of the same conditions for operation and the same conditions restore the system to normal. Partial operation of this modified circuit is obviously obtainable in the same manner by the use of the cancelling button 75

CE, which is inserted in the holding or relay stick circuit and its operation at any time thereby restores the system to normal.

Similarly, in this circuit a by-pass of the automatic cancelling circuit through contacts of relays TR¹ and RP is provided by wire 171, contact 172 of relay 61 de-energized, wires 190, 149 and 127. This provides that automatic cancellation is effective only after the third or green indication has been displayed.

It will now be seen that a communicating system has been provided that may utilize either of the suggested typical circuits in the proposed installation outlined in Fig. 1 and thereby establish communication between the conductors of trains on any track, the gatemen at the associated platform and either train director according to the outgoing direction of the particular train.

Thus, the proposed system fulfills the traffic communication requirements inside large railway terminals and employs a minimum number of individual line wires connecting each platform with the two towers thereby minimizing the cost of installations embodying a large number of platform communicating stations.

The above rather specific description of one form of the present invention is given solely by the way of example, and is not intended in any manner whatsoever, in a limiting sense. It is also to be understood that various modifications, adaptations and alterations may be applied to meet the requirements of practice, without in any manner departing from the spirit or scope of the present invention, except as limited by the appended claims.

Having thus described our invention, what we claim is:—

1. A communicating system for use in railway terminals having a plurality of tracks with loading platforms associated therewith and having train director's towers governing outgoing traffic in each direction therefrom, said communicating system including a plurality of parallel train conductor communicating stations and a plurality of parallel gateman communicating stations associated with each of said tracks, a communicating station for each of said tracks at each of said train director's towers, energy conducting wires commonly connecting each of said platforms and each of said towers, individual wires connecting each platform with each tower whereby electrical circuits can be established between said platforms and said towers and means at said platforms and at said towers whereby sequential inter-communication can be obtained over said electrical circuits between such of said communicating stations as are associated with a common track.

2. A communicating system for multi-track railway terminals, said terminals having two directional traffic controlling towers, a plurality of platforms located for loading trains on tracks adjacent thereto and gates controlling the entrance of passengers to said platform, said communicating system including signalling stations at each of said towers corresponding to each track adjacent said loading platforms, a plurality of parallel signalling stations conveniently located for train conductors at each platform for each track adjacent thereto and a signalling station associated with each of said tracks located at each of said gates, energy conducting wires commonly connecting all of said platforms and said towers, individual wires connecting each of said platforms with each of said towers, electro-

responsive means at said platforms and at said towers whereby circuits including said common energy wires and said individual wires can be sequentially established thereby permitting signal communication between associated stations, said communication being dependent on the presence of a train on the track associated therewith.

3. A communicating system for multi-track railway terminals whereby sequential communication can be established between a train conductor, a train director and a gateman therein, said communicating system including a train director apparatus associated with each track and with each traffic direction thereon, a conductor and gateman signalling apparatus corresponding to each of said train director signalling apparatus, a single source of energy conducted to each of the above signalling apparatus, individual conductors connecting each of said train director apparatus with its associated conductor and gateman apparatus, each of the above apparatus including electro-responsive means arranged to maintain the last communicated signal until the communication of the next sequential signal, and said electro-responsive means further arranged to automatically restore said communicating system to normal upon the departure of a train associated therewith.

4. A communicating system for railway terminals having platforms arranged to load trains on tracks adjacent thereto and having towers governing traffic on said tracks, said communicating system including electro-responsive communicating means at each of said towers and at each of said platforms, a single source of energy conducted to each of said tower communicating means and to each of said platform communicating means, said platform communicating means including a group of associated apparatus for each track adjacent thereto, said associated track apparatus including a group of interrelated relays associated with each of said towers, a plurality of parallel conductor communicating stations each having a group of various signal indicating means associated with each of said groups of interrelated relays and a manually operable circuit controller associated with each of said groups of signal indicating means, a plurality of parallel gateman communicating stations having a traffic direction indicating means associated with each of said groups of interrelated relays and a manually operable circuit controller associated with each of said traffic direction indicating means, and each of said tower communicating means including groups of associated relays which groups are individually connected to its particular corresponding group of relays at said platforms and a tower signalling station associated with each of said tower relay groups which have means indicating various signals and associated manually operable acknowledging and cancelling contacts.

5. A communicating system for multi-track railway terminals whereby communication may be established between a trackway station, a station located at a gate leading thereto and a station associated therewith conveniently located for a train director, said communicating system including electro-responsive apparatus located at said train director station connected by a single wire to similar electro-responsive apparatus at said trackway station, a two wire source of energy having a third wire of relatively equal and opposite potential thereto, said wires commonly connecting all the aforesaid apparatus, a polarized

- relay included in said train director apparatus and in said trackway apparatus, means at said trackway for definitely energizing said polarized relays over said single connecting wire and said 5 common connecting wires, a stick circuit completed by said energizing of a polarized relay and including a resistance unit whereby said polarized relays are held in said definitely energized position and means at said train director station for superimposing a reverse polarity of 10 energy on said polarized relays through a substantially smaller resistance circuit than said stick circuit.
6. A communicating system for railway terminals 15 whereby communication can be established between a trackway station, a gate trackway station located at a gate leading to the trackway station, and a train director station, said communication system including a group of 20 relays associated with the trackway station, and a group of relays at the train director station, the two groups being interconnected by two line wires, communicating means whereby the relays in each of said groups can be progressively energized over said line wires by a sequential energization of the wires, and stick circuits for each 25 of said relays which are complete only during occupancy of an associated track section.
7. Two spaced stations, a polar relay at each 30 station connected in a common circuit, a neutral relay at each station, a pick-up circuit for each neutral relay controlled by one polar position of the polar relay at its station, and a stick circuit for each neutral relay controlled by the other polar 35 position of the polar relay at its station.
8. Two spaced stations, a polar relay at each station connected in a common circuit, a neutral relay at each station, a pick-up circuit for each neutral relay controlled by one polar position of the polar relay at its station, a stick circuit for each neutral relay controlled by the other polar 40 position of the polar relay at its station, and indicating means at each station each selectively controlled by the said relays at its station.
45. 9. In communicating means, in combination, a director's station, and at least one way station, indicating means at each station, a polarized relay at each station, means at the way station for placing one polarity of energy on each of the polar relays to give one indication at each 50 station, means at the director's station to put the other polarity of energy on the polar relays to give another indication of each station, and means at the way station, for then putting energy of said one polarity on the polar relays to give 55 still another indication at each station.
10. In a communicating means, in combination, a director's station, and at least one way station, indicating means at each station, a polarized relay at each station, means at the way station for placing one polarity of energy on each of the polar relays to give one indication at each station, means at the director's station to put the other polarity of energy on the polar relays 60 to give another indication at each station, and a neutral relay at the director's station picked up through the polar relay of its station when energized by said one polarity for controlling said one indication at the director's station.
70. 11. In communicating means, in combination, a director's station, and at least one way station, indicating means at each station, a polarized relay at each station, means at the way station for placing one polarity of energy on each of the 75 polar relays to give one indication at each sta-
- tion, means at the director's station to put the other polarity of energy on the polar relays to give another indication at each station, means at the way station, for then putting energy of said one polarity on the polar relays to give still another indication at each station, and a neutral relay at the director's station controlled by its polar relay and included in the control of said another indication at its station.
12. In combination, a director's station and at least one way station spaced therefrom, a polarized circuit connecting up the stations and including a polar relay at each station, means at the way station for placing energy of one polarity only on each of the polar relays, and means at the director's station for placing energy of the other polarity only on each of the polar relays.
13. In combination, a director's station and at least one way station spaced therefrom, a polarized circuit connecting up the stations and including a polar relay at each station, means at the way station and dependent upon traffic controlled means for placing energy of one polarity only on each of the polar relays, and means at the director's station for placing energy of the other polarity only on each of the polar relays.
14. In combination, a director's station and at least one way station spaced therefrom, a polarized circuit connecting up the stations and including a polar relay at each station, means at the way station for placing energy of one polarity only on each of the polar relays, means at the director's station for placing energy of the other polarity only on each of the polar relays and lock-out means (relay TNP) requiring the initial energization of the polar relays to be controlled from the way station.
15. In a communicating system, a director's station, a plurality of way stations, common power conductors extending to said director's station and to all way stations, individual conductors connecting each way station with the director's station, a first and a second signal transmitting and signal indicating means at each way station, a signal transmitting and signal indicating means at the director's station associated with each of the way stations, electro-responsive storing means at the director's station and at each way station operable to set up a plurality of distinctive conditions in accordance with successive current impulses applied thereto by operations of the various associated signal transmitting means in a particular sequence, and circuit means arranged to condition the various signal indicating means in accordance with the condition of their associated storing means.
16. In a communicating system, a director's station, a plurality of way stations, conductors supplying energy to said director's station and to all way stations in parallel, individual conductors connecting way stations with the director's station, a first and a second signal transmitting and signal indicating means at each way station, a signal transmitting and signal indicating means at the director's station associated with each of the way stations, a group of relays at the director's station associated with each way station, a group of relays at each way station, circuit means energizing the relays in said groups one at a time by successive current impulses applied thereto by operations of the various associated signal transmitting means in a particular sequence, and circuit means arranged to condition the various signal indicating means in accord-

ance with the energization of their associated groups.

17. In a communicating system, a director's station, a plurality of way stations, common power conductors extending to said director's station and to all way stations, each way station having its individual plurality of conductors connecting it with the director's station, a first and a second signal transmitting and signal indicating means at each way station, a signal transmitting and signal indicating means at the director's station associated with each of the way stations, neutral electro-responsive storing means at the director's station and at each way station operable to set up a plurality of distinctive conditions in accordance with successive current impulses applied thereto by operations of the various associated signal transmitting means in a particular sequence, and circuit means arranged to condition the various signal indicating means in accordance with the condition of their associated storing means.

18. In a communicating system, a director's station, a plurality of way stations, common power conductors extending to said director's station and to all way stations, each way station having a single individual conductor connecting it with the director's station, a first and a second signal transmitting and signal indicating means at each way station, a signal transmitting and signal indicating means at the director's station associated with each of the way stations, neutral electro-responsive storing means at the director's station and at each way station operable to set up a plurality of distinctive conditions in accordance with successive current impulses applied thereto by operations of the various associated signal transmitting means in a particular sequence, and circuit means arranged to condition the various signal indicating means in accordance with the condition of their associated storing means.

19. In communicating means, in combination, a director's station, and at least one way station, indicating means at each station, a polarized relay at each station, means at the way station for placing one polarity of energy on each of the polar relays to give one indication at each station, means at the director's station to put the other polarity of energy on the polar relays to give another indication at each station, and means at the way station, and spaced from the first said means at this station, for then putting energy of said one polarity on the polar relays to give still another indication at each station.

20. In communicating means, in combination, a director's station, and at least one way station, indicating means at each station, a polarized relay at each station, means at the way station for placing one polarity of energy on each of the polar relays to give one indication at each station, means at the director's station to put the other polarity of energy on the polar relays to give another indication at each station, means at the way station, for then putting energy of said one polarity on the polar relays to give still another indication at each station, a neutral relay at the director's station controlled by its polar relay and included in the control of said another indication at its station, and a neutral relay at each of the stations controlled by its polar relay and included in the control of said still another indication at its station respectively.

21. In communicating means, in combination, a director's station, and at least one way station,

indicating means at each station, a polarized relay at each station, means at the way station for placing one polarity of energy on each of the polar relays to give one indication at each station, means at the director's station to put the other polarity of energy on the polar relays to give another indication at each station, means at the way station, for then putting energy of said one polarity on the polar relays to give still another indication at each station, a neutral relay at the director's station controlled by its polar relay and included in the control of said another indication at its station, and a slow release neutral relay at each of the stations controlled by its polar relay and included in the control of said still another indication at its station respectively. 5

22. In communicating means, in combination, a director's station and at least one way station, indicating means at each station, a polarized relay at each station, means at the way station for placing one polarity of energy on each of the polar relays to give one indication at each station, means at the director's station to put the other polarity of energy on the polar relays 25 to give another indication at each station, means at the way station, for then putting energy of said one polarity on the polar relays to give still another indication at each station, a neutral relay at the director's station controlled by its polar 30 relay and included in the control of said another indication at its station, a slow release neutral relay at each of the stations controlled by its polar relay and included in the control of said still another indication at its station respectively, 35 and traffic controlled means for restoring all relays to normal.

23. In combination a director's station and at least one way station spaced therefrom, a polarized circuit connecting up the stations and including a polar relay at each station, means at the way station for placing energy of one polarity only on each of the polar relays, means at the director's station for placing energy of the other polarity only on each of the polar relays, and 45 means whereby energization of the polar relays by alternate polarities of energy energizes corresponding and distinctive indications at the way station and the director's station. 40

24. In combination a director's station and at least one way station spaced therefrom, a polarized circuit connecting up the stations and including a polar relay at each station, means at the way station for placing energy of one polarity only on each of the polar relays, means 55 at the director's station for placing energy of the other polarity only on each of the polar relays, lock-out means (relay TNP) requiring the initial energization of the polar relays to be controlled from the way station, and means 60 whereby energization of the polar relays by alternate polarities of energy energize corresponding and distinctive indications at the way station and the director's station.

25. A communicating system for railway terminals whereby communication can be established between a trackway station, and a train director station, said communication system including a group of relays associated with the trackway station, and a group of relays at the 70 train director station, the two groups being interconnected by two line wires, communicating means whereby the relays in each of said groups can be progressively energized over said line wires by a sequential energization of the line 75

wires, the separate energizations each being initiated from a station different from that of the preceding.

26. A communicating system for railway terminals whereby communication can be established between a trackway station, and a train director station, said communication system including a group of relays associated with the trackway station, and a group of relays at the train director station, the two groups being interconnected by two line wires, communicating means whereby the relays in each of said groups can be progressively energized over said line wires by a sequential energization of the line wires, the separate energizations each being initiated from a station different from that of all the others.

27. A communication system whereby communication can be established between two spaced stations, said system including a group of relays associated with each of two stations, the two groups being interconnected by only a single circuit, communicating means whereby

the relays in each of said groups can be progressively energized from one or the other station over said circuit by a sequential energization of the circuit, the separate energizations each being initiated from a station different from that from which the immediately preceding energization was initiated.

28. A communicating system for establishing communication between two spaced stations, said system including a group of neutral relays only associated with one station, and a group of neutral relays only associated with the other station, the two relay groups being interconnected by two line wires, communicating means whereby the relays in each of said groups can be progressively energized from one or the other station over said line wires by a sequential energization of the line wires, the separate energizations each being initiated from a station different from that from which the immediately preceding energization was initiated.
